(57) **CLAIM**

We claim the ornamental design for a beverage cup carrier tray, as shown and described.

DESCRIPTION

FIG. 1 is a top plan view of a beverage cup carrier tray; FIG. 2 is a bottom view of a beverage cup carrier tray of FIG. 1;

FIG. 3 is a top, side and rear view of a beverage cup carrier tray of FIG. 1;

FIG. 4 is a front view of a beverage cup carrier tray of FIG. 1;

FIG. 5 is a front and side elevational view of a beverage cup carrier tray of FIG. 1;

FIG. 6 is a top, front and side perspective view of a beverage cup carrier tray of FIG. 1;

FIG. 7 is a front, side and top perspective view of a beverage cup carrier tray of FIG. 1;

FIG. 8 is a rear view of a beverage cup carrier tray of FIG. 1;

FIG. 9 is a bottom, front and side perspective view of a beverage cup carrier tray of FIG. 1;

FIG. 10 is a side elevational view of a beverage cup carrier tray of FIG. 1;

FIG. 11 is a top, front and side perspective view of a beverage cup carrier tray of FIG. 1;

FIG. 12 is a top, rear and side perspective view of a beverage cup carrier tray of FIG. 1;

FIG. 13 is a bottom, front and side perspective view of a beverage cup carrier tray of FIG. 1 stacked on top of another beverage cup carrier tray;

FIG. 14 is a front and side elevational view of a beverage cup carrier tray of FIG. 1 stacked on top of another beverage cup carrier tray; and,

FIG. 15 is a front view of a beverage cup carrier tray of FIG. 1 stacked on top of another beverage cup carrier tray.
